YARN CARRIER

Ernest A. Feustel, Hasbrouck Heights, N. J.

Application December 24, 1937, Serial No. 181,655

1 Claim. (Cl. 66—126)

The present invention relates to certain new and useful improvements in yarn carriers, and it relates more particularly to yarn carrier tubes for full-fashioned hosiery knitting machines and the like, wherein relatively fine and delicate threads or filaments must be paid out at relatively high linear speeds, and wherein the yarn carriers must work in small spaces with relatively small clearances.

10 In full-fashioned hosiery knitting machines, it has been the practice to provide the yarn carriers or yarn carrier fingers, or yarn guiding fingers with a small, fine-bore tube at the delivery end through which the thread finally passes, and 15 from which the thread is ultimately discharged or paid out across the needle bank in front of the sinkers. These yarn carrier "tubes" have generally been made of iron or steel tubes of suitably small external and internal diameters 20 which have been cut off to suitable lengths and inserted in the end of the yarn carrier or yarn carrier finger.

Some of these yarn carrier tubes of the present practice have also been tempered to increase 25 their hardness, or even case hardened in some instances to increase their hardness;—all in an effort to increase their resistance to wear at the point where the thread crosses the lip of the tube, thereby to increase the life of the tube, and 30 also to minimize injury or damage to the fine threads.

The yarn carrier tubes heretofore used, and particularly used in the full-fashioned hosiery art, are nevertheless deficient to a substantial 35 extent, notwithstanding all the effort up to this time as hereinabove pointed out. Thus, the best yarn carrier tubes now in use in the knitting industry are both subject to substantial wear, and are also injurious, to greater or lesser extent, 40 to the fine threads which they are required to pay out at comparatively high speeds.

Conventional yarn carrier tubes in time form slight depressions or "cuts" or slots across the discharge edge or discharge lip thereof, at two 45 more or less diametrically opposite points where the thread crosses the annular lip or terminal of the tube alternately as the carrier moves to and fro across the needle bank alternately in opposite directions. The threads, particularly 50 the more delicate threads or the threads of comparatively finer gauge or the threads with fewer filaments, or formed of finer filaments, are not infrequently damaged, and in fact broken by faulty or marred carrier tubes, resulting in loss 55 of production both by actual stoppage of the

machines caused by actual break of the thread (and also by the production of "seconds" or imperfect hosiery) and the roughening of the thread which gives roughening, or skiving of the thread which gives striations or irregularities in appearance in the finished hose. This condition is made particularly critical by virtue of the fact that the thread must cross the lip of the conventional yarn carrier tube at almost a right angle, or 90°, with respect to the longitudinal 10 axis of the tube. Moreover, if the slots or "cuts" across the end of the carrier tube become deeper as time goes on, the effective discharge point of the thread is raised upwardly so that the thread in fact may be too high to be engaged by the 15 sinkers particularly in the zones near the selvages where the "lead" of the carrier with respect to the sinkers, or the "lag" of the sinkers with respect to the carrier are gradually diminished, so that the one or more of the end sinkers may 20 not engage the thread but may pass beneath it without engagement. While this may be corrected by lowering the guidance correspondingly as the slots wear deeper, such lowering is not desirable both from the standpoint of labor involved as well as from the standpoint of disturbing 25 the small clearances in which the yarn carrier must work.

In conventional yarn carrier tubes now in general use, and particularly when using high twisted 30 yarns, the "cutting" or the groove or slotting of the yarn carrier tubes is sufficient to necessitate replacement of yarn carrier tubes sometimes from four to six times a year, and this entails 35 a very considerable labor expense in addition to the cost of the new tubes as well as the loss of production while the machines are being refitted with new tubes.

So too, the yarn carrier tubes now in general 40 use have also been found to be deficient insofar as they do not present a smooth and gradual contact surface to the delicate thread passing across the annular discharge lip thereof, at approximately 90° to the longitudinal axis of the tube, even when the tube is in all comparatively 45 new condition, but on the contrary present relatively sharp edges with pronounced corners and present edges of a comparatively abrasive or skiving character which tend to abrade or skive or minutely to "shave" the fine filaments, as they 50 pass the lip of the tube at high speed, thereby tending, more or less to weaken the thread depending upon the extent of such "skiving" or "shaving", and to render the thread somewhat 55 irregular in thickness or weight in the finished

production, thereby tending to create irregularities in appearance of the texture of the hose or to produce what may be called "rings" in the finished hose where thread has been made weaker or thinner in contrast to the other threads. This irregularity in appearance is sometimes made more conspicuous in the production of the so-called "ringless" hosiery or in the production of hosiery with three or more carriers or three or more threads alternated through the body of the hose because of a faulty carrier tube. One of the yarn carriers will cause one of the several threads to be "thinned" slightly or weakened slightly with the result that the slight difference in the weight of the thread will recur at every third or fourth course depending on the number of carriers and threads used. This condition may be accentuated as the tube wears.

The present invention contemplates a yarn carrier tube which will eliminate the deficiencies present in the yarn carrier tubes now in general use, and which will present a gradual and curved bearing surface to the thread as the thread passes across the terminal lip of the tube and the lip of which will be devoid of all abrasive and skiving or "shaving" tendencies both when the tube is new, as well as after substantial use, and one which will not be subject to grooving across the lip of the tube.

With the above and other objects in view, which may appear more fully from the following detailed description and accompanying drawing, the present invention contemplates a composite metallic yarn carrier tube having any suitable metallic tubular body formed of iron, steel or any other suitable metal, and having its discharge terminal portion formed of a ring-like member or an annulus of platinum, iridium, ruthenium or osmium, or the alloys of iridium, ruthenium or osmium with platinum or other suitable alloying metals, united with the tubular body portion preferably by the intervention of a third metal which may be fused to both the body and the terminal annulus, so as to unite the two generally in continuation of each other.

The present invention further contemplates a terminal discharge lip or a yarn carrier tube which will present a curved bearing surface to the thread as it passes across the lip thereof without any square or sharp edges, or without any abrupt change in the direction of the bearing surface such as would necessitate the fine threads making a sharp bend as they emerge from the tube.

The present invention further contemplates and consists of other novel features, as well as other novel details of construction, all of which will appear more fully from the following detailed description and accompanying drawing.

For the purpose of illustrating the invention, there are shown in the accompanying drawing forms thereof which are at present preferred, since the same have been found in practice to give satisfactory and reliable results, although it is to be understood that the various instrumentalities of which the invention consists can be variously arranged and organized and that the invention is not limited to the precise arrangement and organization of the instrumentalities as herein shown and described.

In the accompanying drawing in which like reference characters indicate like parts,

Figure 1 represents a fragmentary perspective view of a yarn carrier in relation to the needle bank and sinkers on full-fashioned hosiery knit-

ting machines having in its lower end a yarn carrier tube embodying the present invention.

Figure 2 represents a section on line 2-2 of Figure 1 on a much enlarged scale.

Figure 3 represents a section on line 3-3 of Figure 2, showing one embodiment of the present invention in yarn carrying tubes.

Figure 4 represents a section on line 4-4 of Figure 2.

Figure 5 represents a section similar to that shown in Figure 4 but showing a slightly modified embodiment of the present invention.

According to the present invention, the yarn carrier tube either in the form indicated in Figures 3 and 4 or in the form indicated in Figure 5 (which figures are many times the actual size) is provided with a tubular body 6, adapted to be inserted into and frictionally retained in the bore 7 of the yarn carrier finger 8, which tubular body 6 may be formed of cold rolled steel, or any other suitable grade of machine steel or tool steel (or any other suitable ferrous or non-ferrous metal). The tubular body 6 has a generally cylindrical outer surface 9, and has a generally cylindrical bore 10 of suitably fine dimensions according to the requirements of the full-fashioned knitting machines now in use. The outer surface of the lower or terminal portion 11 may be slightly tapered, if desired, as indicated in the drawing.

To the terminal of the tubular body 6 a generally annular or ring-like lip member 12 of platinum, iridium, ruthenium or osmium, or a platinum alloy of iridium, ruthenium or osmium, or any other suitable alloy of platinum, iridium, ruthenium or osmium, is permanently secured either by direct fusion with the body 6, or by fusion with an intervening metal 13 which is fused both to the body 6 as well as to the annular lip member 12; said intervening metal 13 being any suitable flux metal or fusion metal, as for instance, gold or a gold alloy, or other suitable fluxing or fusing metal or alloy. If desired, the end of the tubular body 6 may be slightly recessed at a bevel or incline, as indicated at 14 in the drawing, to form a recess for the reception of the fusing metal 13. If desired, the lip member 12 may be similarly recessed although this is not shown in the drawing, and it is preferable to recess only the body member 6.

The lip member 12 is provided at its outer periphery with a lip of generally curved cross-section, as indicated at 15, which presents a curved bearing surface or contact surface to the thread 16, as it leaves the yarn carrier tube.

In Figure 5, there is illustrated a somewhat modified form of the present invention, wherein the terminal side of the annulus 12 is inclined as at 17, so that the effective end of the carrier tube will be approximately horizontal when the tube is at the usual inclination at the yarn carrier finger 8 of the knitting machine so as to permit the setting of the yarn carrier tube to a closer clearance in relation to the rest of the knitting machine parts with which it must cooperate.

While it has not been fully or accurately determined or ascertained just why the novel yarn carrier tube of the present invention produces the remarkable results which it has been found to produce, it is believed that this result may be not merely a matter of hardness of the lip, but may be a matter of the combination of the hardness and texture of the lip, and perhaps may also be a matter dependent upon the frictional relationship between the material of the lip and the

material of the thread which must pass over the lip. Thus, it has been found that these heavier metals, such as platinum, iridium, ruthenium or osmium, and their alloys, as for instance, an alloy of platinum and iridium, or an alloy of platinum and ruthenium, or an alloy of platinum and osmium, or any alloy of two or more of these heavy noble metals, reacts favorably with silk, to minimize both the abrasive action of silk upon the metal and also to minimize the abrasive or wearing action of the metal upon the silk. It was also believed that the crystalline character of steel, of which conventional yarn carrier tubes have heretofore been made, is generally unfavorable to the desired result, partly perhaps because steel includes carbon partly in a free state and partly in the form of carbides, and partly perhaps because the crystalline or granular structure of steel is not sufficiently fine, or is too pronounced. Thus, it is believed that by the use of reasonably hard metals free of carbon, or relatively hard alloys free of carbon, as for instance, the metals and alloys above indicated, a more permanent yarn carrier lip may be produced which will generally eliminate wear both upon the lip, as well as upon the yarn. While the above theoretical explanations of the remarkable results produced by the present invention may not be capable of proof, or may not be disproved or found deficient wholly or in part, the fact remains that by the use of a non-ferrous or a carbon-free hard metallic alloy

or lip on a yarn carrier tube, wear, both upon the lip, as well as upon the yarn, can be substantially eliminated with a resultant saving both in equipment, replacement, adjustment, and maintenance, as well as with the resultant saving of damage to the product, or the resultant increase in perfection of the product. These results are enhanced further by the provision of the rounded or "corner-free" lip, as indicated by the number 15. 5

The present invention may be embodied in other specific forms without departing from the spirit or essential attributes thereof, and it is therefore desired that the present embodiment be considered in all respects as illustrative and not 15 restrictive, reference being had to the appended claim rather than to the foregoing description to indicate the scope of the invention. 10

Having thus described the invention, what is hereby claimed as new, and desired to be secured by Letters Patent, is:

In a full-fashioned hosiery knitting machine, an integral composite yarn carrier tube having an annular platinum-iridium lip, having a curved yarn-contact surface, said annular lip being fused 25 to the body of the yarn carrier tube through a third metal different from that of which the body is formed and also different from that of which the lip is formed.
